(57) **CLAIM**

The ornamental design for an erosion barrier, as shown and described.

DESCRIPTION

FIG. 1 is a top, perspective view of my new ornamental design for an erosion barrier;

FIG. 2 is an exploded, cross-section view taken along line 2-2 in FIG. 1;

FIG. 3 is a bottom, front-side perspective view of the erosion barrier shown in FIG. 1;

FIG. 4 is a back-side plan view of the erosion barrier shown in FIG. 1;

FIG. 5 is a top view of the erosion barrier shown in FIG. 1; FIG. 6 is a bottom view of the erosion barrier shown in FIG. 1; and,

FIG. 7 is a left-side and right-side plan view of the erosion barrier shown in FIG. 1.

The broken lines in the drawing depict portions of the erosion barrier that form no part of the claimed design.
